Primary Examiner—Mitchell Siegel(74) Attorney, Agent, or Firm—Cooley Godward LLP(57) CLAIM

The ornamental design for a golf club head, as shown and described.

DESCRIPTION

FIG. 1 is a perspective view of an embodiment of our new golf club head;

FIG. 2 is an enlarged back perspective view;

FIG. 3 is a back elevational view of FIG. 2;

FIG. 4 is a front elevational view of FIG. 2;

FIG. 5 is a left side elevational view of FIG. 2;

FIG. 6 is a right side elevational view of FIG. 2;

FIG. 7 is a top plan view of FIG. 2; and,

FIG. 8 is a bottom plan view of FIG. 2.

The broken lines in the figures merely illustrate the environment for the golf club head of the present design and therefore form no part of the claimed design.
